UNITED STATES PATENT OFFICE.

GEORGE LEES, OF CHICAGO, ILLINOIS, ASSIGNOR TO HIMSELF, AND CHARLES C. HOVEY, OF BAINBRIDGE, NEW YORK.

APPARATUS FOR CANNING FOOD.

SPECIFICATION forming part of Letters Patent No. 865,021, dated January 1, 1901.

Application filed August 18, 1899. Renewed June 8, 1900. Serial No. 19,624. (No model.)

To all whom it may concern:

Be it known that I, GEORGE LEES, a citizen of the United States, residing at Chicago, in the county of Cook and State of Illinois, have 5 invented a new and useful Improvement in Apparatus for Canning Food, of which the following is a specification.

Articles of various kinds for food have heretofore been steam-cooked and put up in cans 10 from which the air has been exhausted, so that a vacuum has been formed in the can and the can has been sealed by atmospheric pressure.

My present invention relates to improved devices for more effectually cooking and sealing the cans.

In carrying out my invention I provide a vacuum-tank into which a carriage or carrier containing the cans charged with the articles of food are received and secured, and in connection with this vacuum-tank I employ devices that are adjustable and by which the cans may be in part supported or the weight be thrown upon the covers, so as to forcibly keep the same closed, especially before the 25 air is again introduced into the tank to effect the sealing of the cans.

The carriage employed by me is provided with adjustable platforms upon which the cans are supported. These platforms are 30 preferably perforated both for lightness and to provide for any inequalities in the surface of the cover, and in the said vacuum-tank I provide vertical bars with adjustable brackets and said bars are removably connected to 35 vertically-movable rods. These rods engage the vertical bars to which the adjustable brackets are connected either to support the platforms with the cans and their contents or to exert a downward pressure upon the platforms and the cans to keep the covers firmly seated after the vacuum is effected and during the admission of air into the tank.

In the drawings, Figure 1 is a vertical longitudinal section representing my improvements. Fig. 2 is a cross-section at $x x$ of Fig. 1. Fig. 3 is a cross-section through the coupling between the vertically-movable rods and the bars carried by the couplings. Fig. 4 is a partial section and elevation with one part 45 of the couplings removed; and Fig. 5 is an elevation showing the adjustable brackets at

one end of the vacuum-tank, which are of slightly-different form from those at the other end of the tank.

The vacuum-tank is composed of a cylinder a , which may be of any desired length and is provided with a closed end a^2 and with an annular flange 1 at the other end containing a gasket 4. The end a^2 of the tank is removable and is hinged to the annular flange 1, 60 and it is provided with forked lugs 3 and swinging arms 2, having threaded ends, and nuts are pivoted to the annular flange 1, and when the end a^2 is swung to place against the end of the cylinder a and against the rubber gasket 4 the said swinging arms 2 are brought over between the forked lugs 3 and the nuts are tightened to hold the end a^2 securely to the cylinder to form an air-tight closure. Within the cylinder a I provide a track 5 for the wheels of the carriage. The dotted line, Fig. 1, shows that this track may be prolonged by removable sections that are put in place when the end a^2 of the cylinder is swung out of the way. To this vacuum-tank I provide an air-exhaust pipe and valve 6, a steam-inlet pipe 7, a fluid-inlet 8, and fluid-exit 9. Supports 10 are shown for the vacuum-tank, and the same is provided, preferably, with a vacuum-gage 11 and with stuffing-boxes 12, 80 through which stuffing-boxes the vertically-movable rods i pass. The carriage-body b is mounted upon the wheels upon the track 5, and rising from the body b are the guides 13. The platforms or shelves c, c' are above 85 and preferably of the same outline as the body b , and these platforms fit over the guides 13, so that said guides hold the platforms in place.

I do not limit myself to the particular form of adjustable platforms employed upon the carriage b ; but I prefer to perforate the same, so as to accommodate the particular form of can employed by me and which can forms the subject of a separate patent filed simultaneously with the present application. The adjustable platforms may of course be varied, so as to accommodate shapes of cans and conditions which the same make necessary.

I employ bars d, e within the vacuum-tank. The bars d and e , preferably square, are supported from couplings h, h' upon the lower

ends of the vertically-movable screw-rods i '. The lower end of the bar d moves through a bearing in a bracket-arm 16, connected to the fixed head of the vacuum-tank, and the bar e is received in notches in the carriage-body and the adjustable platforms c c' at the other end of the carriage. Upon the bars d e are adjustable brackets d' e' and pressure-brackets f f' .

10 The brackets d' e' serve as supports for the platforms during a part of the operation of creating a vacuum in the cans in the tank, and the brackets f f' come into play to hold down the platforms and the covers of the cans during the admission of air to the tank to seal the cans and hold their covers in place by atmospheric pressure. These brackets d' e' and the pressure-brackets f f' are shown to better advantage in Fig. 2, which shows 20 that they reach laterally across the platforms at either side of the bars d e .

In the operation of my vacuum-tank the carriage b , with its adjustable platforms, is upon a track outside of the vacuum-tank, and 25 in this position the carriage and the platforms are loaded with the cans to be sealed and whose contents are to be cooked or otherwise treated, the platform c bearing upon the lower group of cans and the platform c' upon 30 the upper group of cans. The carriage, with its load of cans, is now run into the vacuum-tank, and the adjustable brackets d' e' are so placed beneath the respective ends of the platforms that said platforms come into close 35 proximity, but free from the lids of the cans, but so close, however, that the action of exhausting the air will not shift the lids or covers of the cans. This movement is effected through the medium of the vertically-movable rods i i' and the couplings h h' , that connect the same to the bars d e , and the hinged end a^2 is swung against the end of the tank and the rubber gasket and the swinging arms are brought over between the forked lugs and 40 strained to apply pressure to hold this movable end with an air-tight seal to the body of the vacuum-tank. The air is now exhausted from the vacuum-tank through the exhaust-pipe 6 to create any degree or extent of vacuum that may be required in the tank. In 45 creating this vacuum of course all air, or the larger percentage thereof, is not only removed from the tank, but from within the cans, above the contents thereof, as well as the air held in the contents of the can. After this 50 vacuum is established the valve shown in the pipe 6 is closed and the rods i i' are rotated and lowered, so as to allow the platforms to descend upon the covers of the cans, and these 55 rods are further lowered to bring the pressure-brackets f f' down tightly upon the top shelf, so as to securely close all of the cans, the pressure being transmitted through the upper group of cans and the platform c to the lower group of cans resting firmly upon the bed of the carriage. When so sealed, the contents of the cans are to be treated ac-

ording to the character of the contents being cooked or otherwise treated. After the cooking or other treatment of the contents of the cans, and especially so where heat is employed, it is necessary to cool the cans, and while the cooking operation is preferably done by steam admitted into the tank through the pipe 7 the cooling-water employed 75 after the cooking is admitted through the pipe and valve at 8 and finds an exit through the pipe and valve 9, or vice versa. After the cans have been cooled and before they can be removed the air must be admitted to the tank, 80 so that the atmospheric pressure can come into effect upon the cans to close the covers securely and hold the same in place, there being, of course, a vacuum within the cans. To do this, and prevent any air accidentally 85 finding access into the cans, I still keep the pressure-brackets f f' in place and the covers held forcibly down upon the bodies of the cans while the air is admitted through the pipe and valve 6 until the pressure within 90 the tank is equal to the pressure without, after which the movable end a^2 is loosened and swung out of place, so that the carriage may be withdrawn from the tank for the removal of its contents, the placing of other 95 cans upon the platform, and the repeating of the operations just described.

The upper ends of the bars d e are provided with eyes, and the couplings h h' are made in two parts and are held together removably by 100 the clamping-bolts 14, and connecting-pins 15 pass through the eyes at the upper ends of said bars and through lugs on the respective parts of the couplings to removably suspend the said bars d e from the couplings, and the 105 upper ends of the couplings are made with sockets and the lower ends of the screw-rods i i' are made with balls to fit said sockets, so that in raising and lowering the bars d e the same may not be turned by the rotation of 110 the rods i i' . While the bar d is nominally a fixture, the bar e is movable, and before the carriage and contents are removed from the tank said bar e must either be removed with its brackets by taking away the pin connecting the same with the coupling h' or the same 115 must be swung up out of the way and be supported in such position to be lowered to place or to be replaced after the carriage and contents are again run into the tank in repeating 120 the operations.

In my improved vacuum-tank it is possible to treat other goods than those contained in cans with closure-covers, and in this connection I would remark that meat of various 125 kinds, such as hams and corn-beef, may be pickled or otherwise treated by being suspended from the platforms of the carriage and run into the tank and the tank closed, and when the air is exhausted from the tank 130 the pores of the meat are opened, so that the air within the meat escapes and is drawn away with the air from the tank and the pickling liquid may be introduced through

and from the pipes 8 9 and the tank filled with the same, which pickling liquid will enter the pores of the meat and permeate the same thoroughly to effect the pickling operation.

5 I claim as my invention—

1. In an apparatus for canning food, the combination with the cylinder, a removable end and a track within the cylinder, of a movable carriage upon said track, guide-bars rising vertically from the carriage and adjustable platforms through which said guide-bars pass, means within the cylinder for supporting the platforms of the carriage and their contents during a portion of the operations employed in the tank and means for holding down the covers of the cans during the admission of air, substantially as set forth.

2. In an apparatus for canning food, the combination with a cylinder, a removable end, a track and a carriage adapted to be moved in and out of the cylinder and to receive cans and their contents for treatment, of guide-bars adjacent to the respective ends of the carriage, brackets connected to said guide-bars for supporting the platforms at their ends and for pressing the same downward, and means connected to the said bars for moving the same and the brackets vertically to perform their various functions, substantially as set forth.

3. In an apparatus for canning food, the combination with a cylinder, a removable end, a track and a carriage adapted to be moved in and out of the cylinder and to receive cans and their contents for treatment, of guide-bars adjacent to the respective ends of the carriage, brackets connected to said guide-bars for supporting the platforms at their ends and for pressing the same downward, and couplings connected to said bars and vertically-movable rods and stuffing-boxes surrounding the same and secured to the cylinder, the lower ends of the said rods being connected to the couplings by a ball-and-socket joint, substantially as set forth.

4. The combination in an apparatus for canning food with a cylinder, a closable end therefor, a track within the cylinder, a carriage adapted to be moved in and out of the cylinder on the track and to hold the cans of goods to be treated, of the vertical bar *d* the guide 16 therefor at the lower end, the vertical bar *e* received in notches in the carriage and platform at the opposite end, the adjustable brackets *d' e'* upon the said bars *d e*, the adjustable pressure-brackets *f f'* upon said bars above the upper platform, couplings *h h'* to which the upper ends of the said bars are removably connected, and which couplings contain sockets, the stuffing-boxes connected upon the outside of the cylinder and the vertically-movable rods *i i'* passing through the stuffing-boxes and having balls or knobs at their lower ends fitting the sockets of the couplings, the couplings *h h'* being made in two parts and the bolts 14 for holding the two parts together removably, whereby the parts may be disconnected to separate the rods from the couplings, and the couplings from the rods *i i'*, substantially as set forth.

ets of the couplings, substantially as and for the purposes set forth.

5. The combination in an apparatus for canning food with a cylinder, a closable end 70 therefor, a track within the cylinder, a carriage adapted to be moved in and out of the cylinder on the track and to hold the cans of goods to be treated, of the vertical bar *d*, the guide 16 therefor at the lower end, the vertical bar *e* received in notches in the carriage and platform at the opposite end, the adjustable brackets *d' e'* upon the said bars *d e*, the adjustable pressure-brackets *f f'* upon said bars above the upper platform, couplings *h h'* to which the upper ends of the said bars are removably connected, and which couplings contain sockets, the stuffing-boxes connected upon the outside of the cylinder and the vertically-movable rods *i i'* passing through the stuffing-boxes and having balls or knobs at their lower ends fitting the sockets of the couplings, the couplings *h h'* being made in two parts and the bolts 14 for holding the two parts together removably, 90 whereby the parts may be disconnected to separate the rods from the couplings, and the couplings from the rods *i i'*, substantially as set forth.

6. In an apparatus for canning food, the combination with the cylinder, a removable end and a track within the cylinder, of a movable carriage upon the track, platforms for tiers of goods in planes parallel with the carriage-platform, and each guided vertically 100 over the said carriage, means within the cylinder for supporting and for adjusting the said platforms as loaded and during a portion of the operations employed in the tank and means for exerting a pressure on the 105 platforms and cans for holding down the covers of the cans during the admission of air, substantially as set forth.

7. In an apparatus for canning food, the combination with a vacuum-tank comprising 110 a cylinder and a closable end, a track within the cylinder, a carriage adapted to receive the goods to be treated and movable on the track in and out of the cylinder, of platforms for the goods above the carriage, devices connected to the upper part of the tank and suspended within the same, said devices acting for supporting the platforms of the carriage and the goods thereon and means for adjusting the said supporting devices for exerting 115 a pressure upon the cans and the platforms for holding down the covers of the cans during the admission of air, a pipe for exhausting the air, a pipe for admitting water for cooling, or other fluid for effecting the operations, substantially as set forth.

8. In an apparatus for canning food, the combination with a vacuum-tank comprising 120 a cylinder and a closable end, a track within the cylinder, a carriage adapted to receive the goods to be treated and movable on the track in and out of the cylinder, of platforms

for the goods above the carriage, vertically-adjustable devices connected to the upper part of the tank and extending therein, devices removably connected thereto within the tank, supports for the platforms connected to the said removable devices and suspended therefrom within the tank whereby the goods are supported from the platforms or a pressure is brought to bear upon the covers of

the cans upon the platforms during the admission of air, substantially as and for the purposes set forth.

Signed by me this 8th day of August, 1899.

GEO. LEES.
